UNITED STATES PATENT OFFICE.

WILLIAM E. WINE, OF TOLEDO, OHIO.

TOP RAIL FOR FREIGHT CARS.

Application filed March 2, 1928. Serial No. 258,648.

My invention relates to new and useful improvements in freight cars and more particularly to the end construction thereof and the top rail.

5 The present invention also contemplates in its broadest aspect, a car of what is known as the "full capacity type", that is, where the ends are slightly tapered or off-set, so that although space is provided on the side 10 for the safety appliances, such as ladders and grab irons, the cubic capacity of the car will be lessened to but a small degree.

There are two principal types of full capacity cars; one, where the end side sheets 15 are slightly set in and extend parallel with each other to the extreme ends of the car and, the other type, where the end side sheets extend at a slight angle towards each other as they approach the end of the car.

20 The latter type is disclosed in the patent to J. H. Pilcher, No. 143,096 and the present invention in its broadest aspect is similar to this Pilcher type of reduced car ends.

One of the objects of the present invention 25 is to form the end side sheets of plane surfaces and dispose them slightly at an angle towards each other as they approach the end of the car and, to further provide a top rail which is provided with a trough like portion throughout the greater part of its length, this trough-like portion however, dying away 30 and merging near its ends with the vertically extending portion of the top rail.

In a number of my former applications and 35 co-pending applications, there are shown the end side sheets provided with certain trough-like portions, while in this application the trough-like portion is formed in the top rail and the end side sheets are plain surfaces.

40 These trough like portions provide for a maximum capacity and also prevent formation of pockets in the sides of the car in which the coal might lodge when unloading.

As is well known to those skilled in the art, 45 these cars are often emptied by strapping the car to a platform and the entire car and platform inverted so that the coal passes out from the top of the car rather than through the hopper bottoms.

50 Still another object of the invention, therefore is to provide a top rail for a freight car, to which is secured the end side sheets, the top rail being formed with the trough-like portion which vanishes near its ends. Furthermore, the top rail and end side sheets are 55 arranged so that space will be provided for

the safety appliances which must of course come within certain limits as called for by the Master Car Builders' Association.

With these and other objects in view, as 60 will be fully explained as the specification proceeds, the invention consists in certain new and novel arrangements and combination of parts as will be hereinafter more fully described and pointed out in the claims. 65

Referring now to the drawings showing a preferred embodiment,

Fig. 1 is a fragmentary side elevation of a freight car showing the manner of forming the top rail and the end side sheets together 70 with the disposition of the ladder.

Fig. 2 is a fragmentary top plan view of the top rail, the dotted lines showing the disposition of the end side sheets at the one end of the car at its one side. 75

Fig. 3 is a sectional view of the top rail and portion of the end side sheet, as seen on line 3—3 of Figure 1.

Fig. 4 is a sectional view taken on line 4—4 of Fig. 1 looking in direction of the arrows, 80

Fig. 5 is a sectional view taken on line 5—5 of Fig. 1 and

Fig. 6 is a horizontal section taken on line 6—6 of Figure 3.

Referring now more specifically to the several views, there is shown in Figure 1, a fragmentary side elevation of the side of the car at its one end, and it might be mentioned at the out-set, that the opposite side will be formed in a like manner. Furthermore the 85 sides near the opposite end of the car are also similarly constructed, so that a description of that portion shown in Figure 1 will apply and be a description of both sides of the car at the opposite ends. 90

Referring now to the upper portion of Figure 1, there is seen a top rail 1, the cross section of which is clearly shown in Figure 3.

There will be seen the sloping upright portion or web 2, which is then bent into a horizontal plane 3, forming the upper surfaces of the top rail and is then bent downwardly again to form the over-hanging flange 4. 100

Formed integral with the web 2 is the vertical downright extending leg or flange 5, to which leg will be secured the upper edge of the side sheets 6.

In a like manner the upper edge of the end side sheets 7 will also be secured along this flange portion 6 where the flange extends behind the said end side sheets. 110

This top rail through-out the greater por-

tion of its length will appear in cross section as is shown in Figure 3. Of course uprights or stakes 8 will lie behind the side sheets at certain points and the stakes will extend up 5 behind the sloping portion 2 of the top rail to brace the same while rivets of course will tie the side sheets, top rail and stakes together. This will be understood from Figures 1, 3 and 6.

10 Figures 4 and 5 show the changing contour of the top rail as it approaches its end and also show the end side sheets riveted to the lower portion of the top rail.

Referring for the moment to Fig. 2, the end 15 side sheet 7 is shown in dotted lines as extending from the stake 8 to a corner post 9, the angle of which post is slightly opened so that its two legs will be respectively parallel with the end of the car 10 and with the end 20 side sheet 7. In this Figure 2 there is shown the corner brace 11 which will be riveted to the top rail extending across the end of the car and also to the one that extends along the side of the car.

25 It will also be understood as previously mentioned that the opposite side of the car at its end is similar to the side shown in Fig. 2, but of course its end side sheets extend inwardly as it approaches its corner post.

30 Referring for the moment to the downwardly extending flange 4 of the top rail, (Fig. 1), it will be seen that this is slightly cut away as at 12, so as to provide clearance for the styles 13 of the ladder. This ladder being set nearly flush with the end side sheets 35 and the end side sheets being angularly disposed, permits the ladder to not extend beyond the sides of the car. On the other hand but little space is lost in inclining the plates in this manner to receive the ladder. In 40 other words, the cubic capacity of the car is but slightly reduced as will be clearly understood.

Referring to Fig. 1, it will be seen that the 45 end side sheet 7 is substantially a plane surface and has its upper edge riveted to the leg portion 5 of the top rail, so that these sheets may be simply cut out from ordinary stock and riveted into position unless some special construction is desired for its lower edge.

50 The construction however of the top rail from the stake 8 to the corner posts 9 is of great importance. It will be seen from Figure 1, as well as the several sections that the trough portion 2 from a point opposite the stake 8 tapers and dies away to a vanishing point as at 14.

55 At the point 16 where the trough portion starts to vanish, there will be an ever increasing portion 17, which will extend in a vertical plane as may be understood from Figures 1 and 5. Figure 5 shows the cross section substantially at the end of the top rail.

60 By providing this trough-like portion in 65 the top rail rather than in the end side sheets,

the cost of forming the same may be slightly less than forming the trough portions in the end side sheets and at the same time the assembly of the several parts may be easily accomplished.

70 There is shown a line of rivets 18 which pass through the end side sheets and the leg portion 5 of the top rail, these rivets being in a straight line throughout the side of the car.

75 Also by forming the top rail in this manner it will be seen that the trough-like portion in the top rail extends right up to one of the styles of the ladder, so that the capacity of the car will be as great as possible and at the same time, by having the trough vanish in the top rail at this point, clearance is provided for the styles of the ladder and the rungs will not extend out beyond the natural sides of the car. Small brackets 19 as shown in Fig. 3 80 85 will be disposed at different points beneath the top rail to properly brace the same.

90 It is to be remembered that the end side sheets extend towards each other as they approach the end of the car and the change in contour of the top rail will start substantially at the stake 8 and then change its cross sectional shape progressively to about the point 14 where it continues in the shape shown in Fig. 5 to its end where it is fastened 95 to the corner post 9.

95 It will thus be seen that I have provided a freight car, the side sheets of which are secured to the lower portion of the top rail, which top rail is so formed at its opposite 100 ends that space will be provided for a ladder and at the same time will have a trough-like portion therein, so that the cubic contents of the car will be as great as possible.

105 Lastly the riveting of the end side sheets to the top rail is easily accomplished as the upper edges of the end side sheets simply overlap the lower edge of the portion of the top rail.

110 Many slight changes might be made, without in any way departing from the spirit and scope of the invention.

Having thus described my invention what I claim as new and desire to secure by Letters Patent is:—

115 1. A top rail for a freight car comprising a top portion and a web, the said web extending at an acute angle to the top portion throughout the greater portion of the length of the rail and the end of the rail having its top portion extending at right angles to the web.

120 2. A top rail for a freight car comprising a top portion and a web, the said web extending at an acute angle to the top portion throughout the greater portion of the length of the rail and the opposite ends of the rail having its top portion extending at right angles to the web.

125 3. A top rail for freight cars comprising

a web, a lower vertical portion and a top portion at right angles to the lower vertical portion, the said web being at an acute angle to the top portion throughout the greater 5 length of the rail, the web merging with the lower vertical portion and extending in the same vertical plane therewith at the end of the rail.

4. A top rail for a freight car comprising 10 a top portion and a web, the ends of the rail being slightly inclined from the longitudinal axis of the rail, the major portion of the rail having the web extending at an acute angle to the top portion and the inclined 15 ends of the rail having the web portion at right angles to the top.

5. A top rail for a freight car comprising a lower leg, an upwardly extending web, a horizontal top portion and a downwardly 20 extending flange merging with the top portion and parallel with the lower leg.

6. A top rail for a freight car comprising a web, a lower leg merging with the web and an upper portion merging with the web and 25 having a downwardly extending flange spaced from the web and the web as it approaches the end of the rail extending at right angles to the upper portion of the rail and parallel with the downwardly extending 30 flange.

7. A top rail for a freight car having a trough-like portion formed by an inclined web, the said trough-like portion extending to a vanishing point near the end of the rail, the web being disposed vertically at the end 35 of the rail and extending to a vanishing point near a point where the trough-like portion of the web starts to decrease.

8. A freight car, the end side sheets of 40 which are inclined towards each other as they approach the end of the car, a top rail

having a lower vertical flange, to which the respective end side sheets are secured, the said top rail having a trough-like portion decreasing in width as it approaches the end 45 of the car.

9. A top rail for a freight car comprising a lower leg and an end side sheet secured to said leg, the said top rail at its end having a web that changes from the vertical progressively to an acute angle.

10. A top rail for a freight car comprising a web, a flange merging with the lower portion of the web, a horizontal top portion merging with the web and a downwardly extending flange from said top portion and cut away near the end of the rail, the said web changing its angle of inclination along a line drawn diagonally from the bottom of the web to the top thereof to form a trough-like portion in the said rail and the lower leg of the top rail remaining vertical 60 throughout its length.

11. A freight car having end side sheets extending towards each other as they approach the end of the car, the said end side sheets being plane along their upper portions, a top rail extending above said end side sheets and a trough-like portion formed in said top rail extending partly over the end 70 side sheet.

12. A freight car having oppositely tapered ends, end side sheets inclined towards each other at said ends, a top rail extending along the sides of the car, trough-like portions formed in the top rail and the trough-like portions reaching a vanishing point near the ends of the rail and beyond the inner vertical edges of the end side sheets.

In testimony whereof I affix my signature.

WILLIAM E. WINE.
